CLAIM

The ornamental design for a stand for monitor as shown and described.

DESCRIPTION

FIG. 1 is a front, right perspective view of a stand for monitor showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear, left, top exploded perspective view thereof, showing that a cover on the rear surface of the stand for monitor separates, such that a cable can be kept tidy inside the cover, ensuring a neat exterior of the stand for monitor. The broken lines depict portions of the stand for monitor that form no part of the claimed design.
